ENGINE-STOP MECHANISM.

1,174,226.

Specification of Letters Patent.

Patented Mar. 7, 1916.

Application filed September 19, 1910. Serial No. 582,623.

To all whom it may concern:

Be it known that I, EDGAR H. BRISTOL, a citizen of the United States, and a resident of Naugatuck, in the county of New Haven, 5 State of Connecticut, have invented an Improvement in Engine-Stop Mechanisms, of which the following description, in connection with the accompanying drawings, is a specification, like letters on the drawings 10 representing like parts.

This invention relates to new and useful improvements in engine stop mechanisms, and has for its object, among other things, to provide means whereby an engine may 15 be stopped readily from different stations if desired.

The character of this invention may be best understood by reference to one practical embodiment shown for illustration in the 20 accompanying drawings, in which—

Figure 1 is a front elevation of a governor mechanism embodying the invention; Fig. 2 is a side elevation thereof; Fig. 3 is a detail horizontal section on a line 3—3 of Figs. 1 25 and 2; Fig. 4 is an enlarged detail of parts shown in Fig. 2; and Fig. 5 is a detached detail hereinafter explained.

Referring to the drawings, the governor post 1 has mounted thereon a ball governor 30 of the usual type comprising a fixed collar 2, a sliding collar 3, ball rods 4 connected with the fixed collar 2 at one end and to the sliding collar 3 by the links 5, and the balls 6 secured to the rods 4. A rock shaft 8 is 35 journaled in a bracket 7 and has an arm 9 fixed thereon, which is connected with the valve mechanism (not shown) for admitting steam to the steam chest, by the valve rod 10. Loose on said rock shaft is an arm 11 40 having a weight 12 adjustably mounted thereon, and the arm 13 to which is connected one end of the rod 14 that has a laterally projecting pin 15 in its other end. This pin projects into a cam slot 16 in one 45 side of the governor post, and by its movement therein actuates the rock shaft 8. The governor rod is preferably made in two parts (see Fig. 5), an upper section 17 connected with the collar 3 by the bolt 21; and a lower section 18, secured to a block 19 (see Fig. 2) mounted on the arm 11 and having a rod 20 projecting downwardly therefrom which connects with the cam pin 15.

It may be assumed that the governor rod 50 is in one piece. In Figs. 1 and 2 the parts

are shown in the relative positions occupied by them when the engine is running under normal conditions. If by reason of variation in the load, or for any other cause, the speed of the engine is increased, the balls 6 60 of the governor swing outwardly, thereby raising the collar 3, and through the governor rod connection, the cam pin 15, which pin will move upwardly in the cam slot 16 and actuate the valve mechanism through 65 the arm 9, rock shaft 8 and valve rod 10, shutting off some of the steam supply and decreasing the speed of the engine until it returns to its normal speed, when the pin 15 will return to its original position. If the 70 speed increases to such an extent that the pin 16 is brought to the top of the cam slot 16 the steam supply will be entirely shut off and the engine will stop automatically, at which time the balls will drop by gravity 75 returning the pin 15 to the position shown in Fig. 2, when the engine will automatically start up again. If the governor mechanism should break, the collar 3, aided by the weighted lever 11, will move the governor 80 rod downwardly so that the pin 15 will drop to the bottom of the slot 16, at which time the steam supply is entirely shut off. The value of this mechanism is its ability 85 to automatically control the speed of the engine, and it is one of the objects of my invention to utilize this device by adding means thereto to automatically stop the engine from any one of a number of places located at a distance from the engine itself. 90 To this end the two-part governor rod referred to is provided with a coupling device including a sleeve 24 (see Figs. 3 and 4) connected to the lower section 18 of said governor rod and adapted to receive the lower 95 end of the upper section 17 of said governor rod. This upper section 17 may be detachably retained in said sleeve by a latch 25, pivoted at one end to lateral ears 26 integral with said sleeve, and through a transverse slot in said sleeve normally enters a notch 27 (Fig. 5) in said upper section 17 and thereby couples the sections 17 and 18 together. The latch 25 is normally retained in this position against the resistance of a 100 spring 28 by the hook end 29 of a trip lever 30 fulcrumed between its ends on a lateral arm 31 integral with said sleeve. To release this lever and thereby permit the latch to fly 105 out into the position shown in dotted lines 110

in Fig. 3, the opposite end of said lever may constitute an armature 32 which may be attracted by a coil magnet 33 mounted on an arm 34 also integral with said sleeve. This magnet is connected by wires 35 to a battery 36 and may be excited at will by opening and closing the electric circuit by any one of a plurality of push buttons 37 (Fig. 3), which may be stationed at points remote from the engine as desired.

When the parts are in the positions just described, and as shown in the drawings, the sections 17 and 18 of the governor rod are separably secured together, practically forming a single rod, and it is apparent that if this connection is broken the lower section 18 will drop by gravity, shutting off the steam supply and stopping the engine, through the action of the cam pin 15 and the mechanism connected therewith. This result is accomplished by pressing any one of the push buttons 37, which closes the electric circuit, thereby exciting said coil and attracting the armature of the lever 30, 25 rocking the latter and releasing its hook end 29 from the latch 25, the latter being drawn out of the slot 27 by the spring 28. As soon as the latch is disengaged from the notch 27, which disengagement is facilitated 30 by the angular sides 27^a thereof, the governor rod section 18 drops of its own weight, aided by the weighted lever 11.

It will be understood that my invention is not limited to the particular embodiment shown herein, but that various modifications may be made without departing from the spirit of my invention.

Claims:

1. A stop mechanism for engines comprising, in combination, a governor; cam means having steam varying and stop portions; follower means coöperating with the latter for connection with the engine valve; means connecting said follower means with said governor including separable members; means detachably connecting said members; and means for moving said follower from said steam varying portion of said cam to the stop portion thereof on separation of said members.

2. A stop mechanism for engines comprising, in combination, a governor; and means for connecting the same with the valve of the engine including separable members 17

and 18; a camway 16, a pin 15 coöperating 55 with said camway and connected to the member 18, coupling means detachably connecting said members and an arm 11 and weight 12 tending to move said pin 15 toward the bottom of the cam 16 to close the 60 valve and stop the engine.

3. A stop mechanism for engines comprising, in combination, a governor; means connecting said governor to the engine valve including separable members; a sleeve 65 bracket fast on one of said members and adapted to receive the other; a latch pivoted to said bracket having provision for locking said members together; spring means tending to open said latch; a magnet and an 70 armature trip member pivoted on said bracket and adapted to release said latch to said spring on the energization of said magnet.

4. A stop mechanism for engines comprising, in combination, a governor, a guide having steam varying and stop portions, a follower movable along said guide, a weighted arm tending to move said follower into said stop portion, separable members connecting 80 said governor with said follower, and means detachably connecting said members having provision for separating the latter to permit said weight to move said follower from said steam varying portion to said stop portion 85 for operating the valve of the engine to arrest the latter.

5. A stop mechanism for engines comprising, in combination, a governor, a guide having steam varying and stop portions, a follower movable along said guide, means tending to move said follower into said stop portion, separable members connecting said governor with said follower, and means detachably connecting said members having 95 provision for separating the latter to permit said means to move said follower from said steam varying portion to said stop portion for operating the valve of the engine to arrest the latter.

In testimony whereof, I have signed my name to this specification, in the presence of two subscribing witnesses.

EDGAR H. BRISTOL.

Witnesses:

LAURENCE A. JANNEY,
WATSON E. GOODYEAR.

Copies of this patent may be obtained for five cents each, by addressing the "Commissioner of Patents, Washington, D. C."

It is hereby certified that Letters Patent No. 1,174,226, granted March 7, 1916 upon the application of Edgar H. Bristol, of Naugatuck, Connecticut, for an improvement in "Engine-Stop Mechanisms," were erroneously issued to The Industrial Instrument Company, of Waterbury, Connecticut, a corporation of Connecticut, whereas said Letters Patent should have been issued to *The Foxboro Company, of Foxboro, Massachusetts, a corporation of Massachusetts, as assignee, by mesne assignments*, of the entire interest in said invention, as shown by the record of assignments in this office; and that the said Letters Patent should be read with this correction therein that the same may conform to the record of the case in the Patent Office.

Signed and sealed this 18th day of April, A. D., 1916.

[SEAL.]
